UNITED STATES PATENT OFFICE.

JOSEPH MARTIN, OF MIDLAND, OHIO.

COMBINED HORSE-COLLAR AND HAME.

No. 847,090.

Specification of Letters Patent.

Patented March 12, 1907.

Application filed August 29, 1906. Serial No. 332,525.

To all whom it may concern:

Be it known that I, JOSEPH MARTIN, a citizen of the United States, residing at Midland, in the county of Clinton and State of Ohio, have invented new and useful Improvements 5 in a Combined Horse-Collar and Hame, of which the following is a specification.

This invention relates to combined horse-collars and hames; and one of the principal 10 objects of the same is to provide a hame with a suitable padding to bear against the shoulders of a horse, and thus dispense with the use of a horse-collar.

Another object of my invention is to provide 15 means for rendering the harness less burdensome for the animal in dispensing with the usual heavy horse-collar. In warm weather it is particularly uncomfortable to animals to wear the heavy padded collar, especially when heavy hames are connected 20 thereto. By the use of a combined hame and collar made in accordance with my invention much of the weight is taken from the neck of the animal and the animal is permitted 25 free movement without the galling effects of the heavy collar.

The objects and advantages above referred to are attained by means of the construction illustrated in the accompanying drawing, in which—

Figure 1 is a front elevation of a combined horse-collar and hame made in accordance with my invention. Fig. 2 is a similar view of the hame member before the padding 35 is attached thereto. Fig. 3 is a sectional view on the line 3 3, Fig. 1, looking in the direction of the arrow.

Referring to the drawing for a more particular description of my invention, the numeral 40 1 designates a hame, which may be formed of wood and provided with recesses or shoulders 2 3 at the opposite sides thereof. A rounded enlargement 4 is formed on the

outer curved side of the hame, and the inner bearing-surface is curved, as at 5, to provide 45 a recess for the pad. The pad 6 is connected to the hame by first securing the inturned edge 7 by means of tacks or other suitable fastenings 8 against the shoulder 2. The pad is then drawn around the hame to fit 50 within the curved portion 5, and the opposite end is then secured against the shoulder 3 by means of tacks or fasteners 9. In this way the tacks or fasteners 8 are covered within the pad to prevent the projection of abrading 55 surfaces. The usual trimmings may then be applied to the hame.

From the foregoing it will be obvious that a combined collar and hame made in accordance with my invention will be easy upon an 60 animal, will be light in weight, strong and durable, and will materially reduce the cost of the harness.

Having thus described the invention, what I claim is—

The herein-described combined horse-collar and hame consisting of wooden hame-sections, each having a recess and shoulder at the opposite edges thereof, an enlargement 70 formed near the outer edge of said hame-section, and a curved recess extending longitudinally of the hame between the shoulders, and a pad secured to one of said shoulders by fastening means driven through the inner side of the pad and into the hame, and the 75 other edge of the pad being secured by fastenings driven from the outer side of the pad into the hame, said pad being disposed in the curved recess extending longitudinally of the hame, substantially as described. 80

In testimony whereof I affix my signature in presence of two witnesses.

JOSEPH MARTIN.
